UNITED STATES PATENT OFFICE.

HARRY M. SALYER, OF NEWARK, NEW JERSEY, ASSIGNOR TO AMERICAN PERFORATED MUSIC COMPANY, A CORPORATION OF NEW YORK.

PERFORATING APPARATUS.

No. 918,376.

Specification of Letters Patent.

Patented April 13, 1909.

Application filed July 2, 1907. Serial No. 381,904.

To all whom it may concern:

Be it known that I, HARRY M. SALYER, a citizen of the United States, and resident of Newark, in the county of Essex and State of New Jersey, have invented certain new and useful Improvements in Perforating Apparatus, of which the following is a specification.

The object of my invention is to provide an apparatus wherein one sheet, or a plurality of sheets simultaneously, may be perforated, the operation of perforating such sheets being controlled automatically by a master sheet or pattern, whereby the perforations previously made in the master or pattern sheet will be correspondingly reproduced in a sheet or several sheets for stock or use, as in self-playing musical instruments such as those commonly called automatic pianos, piano players, and the like, and in accordance with my invention the perforations in the stock sheets may be made to accord in dimensions and spacing with those of the master sheet, or be increased or diminished in dimension and spacing as required.

A further object of the invention is to provide in said apparatus means for reproducing master or pattern sheets from an original master or pattern sheet, as distinguished from reproducing stock perforated sheets.

A further object of the invention is to permit the winding of the perforated sheets upon their respective reels directly as the perforations are made in the sheets, in such manner that the perforated sheets will be ready for use directly in the appropriate musical instrument without the necessity of rewinding the previously perforated sheets upon the music rolls, as has heretofore been customary so far as I am aware. To this end I pass the master perforated sheet or pattern across the bridge of the apparatus in the reverse direction of rendering of the musical composition, as by passing the master sheet backward through the apparatus, so that the sheets to be perforated will be perforated reversely to the proper notation of the musical composition, as from the ending of the composition to its beginning, and such reversely perforated sheets are wound directly upon the music roll spools as the perforating is accomplished so that when the completely perforated sheet is fully wound on its spool the commencement of the musical composi-

tion therein perforated will be at the outer end of the music roll ready for use in usual manner.

My invention comprises the novel details of improvement and the arrangements and combinations of parts that will be more fully hereinafter set forth and then pointed out in the claims.

Reference is to be had to the accompanying drawings forming part hereof, wherein,

Figure 1 is a side elevation of a music sheet perforating apparatus embodying my invention. Fig. 2 is an end elevation thereof, looking from the left in Fig. 1. Fig. 3 is a sectional plan view of the apparatus, on line 3, 3, of Fig. 1, Fig. 4 is a side elevation looking at the side opposite that shown in Fig. 1. Fig. 5 is a longitudinal section showing the apparatus fitted for perforating a plurality of sheets for stock or use, Fig. 6 is a similar view illustrating the operation of reproducing a master sheet or pattern, Fig. 7 is a partly broken detail view of a portion of the bridge, illustrating means for adjusting the same, Fig. 8 is a detail section on the line 8 in Fig. 7, Fig. 9 is a detail plan view of part of the bridge, Fig. 10 is a detail plan view illustrating part of the punch-controlling devices, Fig. 11 is a sectional view thereof, Fig. 12 is a partly sectional view of the roll or drum for controlling the master sheet or pattern, Fig. 13 is a detail sectional view of the valve for controlling the punches for perforating rows of holes near the edges of a duplicate master sheet. Fig. 14 is a cross section, enlarged, of the bridge, Fig. 15 is a detail face view of pneumatics for controlling the punches, part being broken away. Fig. 16 is a section on the line 16 of Fig. 15, enlarged, Fig. 17 is an edge view, partly broken, of a modification of said pneumatics, Fig. 18 is a sectional view through Fig. 17. Fig. 19 is a detail end view, illustrating a gripper for moving the stock sheets across the punches, showing the gripper retracted from the sheets. Fig. 20 is a substantially similar view, partly in section, showing the gripper engaging the sheets, Fig. 21 is a detail plan view of Fig. 20, Fig. 22 is a side view illustrating the means for winding the perforated stock sheets upon their respective music rolls, Fig. 23 is a plan view thereof, Fig. 24 is a detail sectional view of the support for one end of the music roll, Fig. 25 is a detail

sectional view of the opposite end of the music roll and its driving shaft, Fig. 26 is a section on the line 26 in Fig. 25, Fig. 27 is a longitudinal sectional view illustrating, partly diagrammatically, the supporting reels for the stock sheets, the sheet perforating devices, and the music roll winding device. Fig. 28 is a detail of a perforated stock sheet, Fig. 28^a is a detail of a duplicate master sheet, Fig. 29 is a detail view illustrating means for providing slack in the sheets to be perforated between their reels and punches, Fig. 30 is a plan view thereof, Fig. 31 is a detail cross section showing the supports of the reel for the sheets, and Fig. 32 is a detail of the means for driving a roll for a sheet.

Similar characters of reference indicate corresponding parts in the several views.

In the accompanying drawings, the numeral 1 indicates a suitable frame, and at 2 is a suitable bridge or tracker which is provided with a series of orifices 2^a, shown arranged in a straight line, and across which the master music sheet or pattern 3 passes. Said master sheet is supported upon a suitable reel 4 shown carried upon brackets 5 of frame 1; any suitable means being provided to permit ready insertion of the master reel in and removal from its supports.

The shaft 6 for reel 4 is provided with a sprocket wheel 7 receiving a chain 8 that passes over a sprocket 9 connected with a friction pulley 10 supported upon an arm 11 pivotally carried by frame 1, for rewinding the master sheet when required, as herein-after explained. The master sheet passes from its reel 4 under a guide roll 12 and from thence over bridge 2 to the controlling drum or roll 13.

Roll 12 may be detachably supported in frame 1 to permit the ready placing of master sheet 3 thereunder. Bridge 2 is mounted to have lengthwise adjustment in frame 1 to cause the orifices 2^a to be adjusted transversely of the master sheet to accord with the perforations in such sheets, and for this purpose I have shown a screw-threaded rod 14 secured to bridge 2 by a pin 14^b and passing freely through a hole in frame 1 and having a nut 14^a bearing against said frame, an expanding spring 15 being interposed between said bridge and frame 1 tending to push the bridge (see Figs. 3 and 7), the pin 16 at the opposite end of bridge 2 being journaled to slide in a suitable hole in frame 1, said pin having a collar 16^a provided with a pin 16^b sliding in a hole in frame 1 to prevent the bridge from turning. By turning nut 14^a to the right or left, bridge 2 may be adjusted across frame 1 the desired distance respecting the perforations of the master sheet. The master sheet drum 13 is secured to shaft 17 journaled in suitable bearings in frame 1, and said drum is made longitudinally expandible to vary the distance be-

tween its circular rows of pins 13^a to cause them to fit the rows of holes 3^a near the edges of the master sheet that may vary in the distance between them, and for this purpose I make drum 13 in two parts 13^b, 13^c, the part 13^b being secured to shaft 17 and telescoping with part 13^c, the latter part having free movement along shaft 17, pin 19 on one part entering the slot 20 in the other part to cause rotation of part 13^c by and with part 13^b while permitting endwise relative adjustment of said parts. Shaft 17 is provided with threads 17^a receiving a nut 21 which engages a hub 13^d on part 13^c and supports the adjacent end thereof, a spiral spring 22 within part 13^c bearing against the latter and against part 13^b tending to separate said parts. By rotating nut 21 the rows of pins 13^a of roll 13 may be caused to approach or recede as required to cause said pins to properly enter the holes 3^a of master sheet 3, (see Fig. 12). The diameters of the parts 13^b, 13^c are substantially equal so that the working surface of roll 13 shall be substantially uniform.

Shaft 17 is to be rotated step by step to correspondingly advance sheet 3, and for this purpose I have shown a ratchet wheel 22 secured upon shaft 17 and engaged by the spring pressed pawl 23 carried by a rock arm 24 pivotally supported concentric with or upon shaft 17 and connected by a link 25 with a crank pin 26 on a shaft 27, suitably journaled on frame 1 and provided with a loose pulley 28 and a clutch, whereby as shaft 27 rotates, dog 23 and ratchet 22 will cause shaft 17 and drum 13 to rotate step by step to correspondingly advance master music sheet 3.

To provide the proper amount of slack in master sheet 3 between the orifices of bridge 2 and the pins 13^a, to cause said pins to properly register with the orifices of the bridge, I provide an adjustable bar or the like 29, pivotally supported upon frame 1 and extending over sheet 3 between bridge 2 and drum 13, said bar being eccentrically disposed and preferably removably supported to permit the ready insertion thereunder of sheet 3. The pintle 29^a of bar 29 is supported in the bearing 30 of frame 1, and the opposite end 29^b of said bar is inserted in a socket in a short shaft 31 journaled on frame 1, (see Fig. 3), and provided with a handle 31^a for turning bar 29, which shaft 31 may be held in set position by a nut 32. By suitably turning bar 29 the length of sheet 3 between orifices 2^a of the bridge and pins 13^a of drum 13 may be increased or decreased as required to cause proper tracking of the master sheet across the orifices of the bridge.

After master sheet 3 passes from drum 13 it is wound on a reel 33 shown supported on uprights 34 of frame 1, and said sheet is shown passing under a detachable idle roll

35, suitably supported in frame 1, to cause the master sheet to lie on drum 13 a considerable distance. Takeup reel 33 is revolved as required to wind up sheet 3. For this purpose I have shown arm 24^a (which extends from arm 24) pivotally connected by a link 36 with a rock arm 37 hung upon a shaft 38 journaled in suitable supports on frame 1, a ratchet wheel 39 secured on shaft 38 being 10 engaged by a spring pressed dog 40 carried by arm 37, whereby shaft 38 is rotated step by step coincidentally with drum 13. Shaft 38 also carries a pulley 41 receiving a belt 42 that passes over a pulley 43 on the shaft of 15 takeup reel 33 whereby the latter is rotated, and the arrangements are such that belt 42 will slip on pulley 43 when necessary to properly wind sheet 3 on reel 33 as the diameter of the sheet thereon increases.

20 To rewind sheet 3 upon its reel 4, when desired, the friction pulley 10 is adapted to engage pulley 28 or its belt to operate pulley 7 through chain 8, and to this end I journal a shaft 44 in frame 1 and to an eccentric pin 45 25 on said shaft I connect a link 46 with arm 11, (see Figs. 3 and 4), and I provide shaft 44 with a crank or handle 47 for rocking the same as desired. By turning shaft 44 to cause frame 11 to swing pulley 10 against 30 pulley 28 the master sheet may be rewound on its roll as much as desired at any time, but normally pulley 10 will be held out of engagement with pulley 28. When sheet 3 is 35 rewound belt 42 may be slipped off its pulley and the sheet disengaged from parts 12, 29, 13 and 35.

To cause the stock sheets 48 to be perforated in accordance with the perforations in master sheet 3, I provide the following arrangement: At 49 are a series of punches arranged in a straight line across the machine and located in suitable holes in a guide 50 extending across frame 1 above a die 51 that is provided with holes 51^a to receive punches 49, a space 52 being provided between guide 45 50 and die 51 for the passage of the stock sheets 48, (Figs. 5 and 11). The punches 49 are controlled by a reciprocative head 53 that is guided at its ends in suitable guides 54 50 on frame 1, and said head is pivotally connected by a link 55 with an eccentric or crank 56 on shaft 27. Head 53 is shown provided with a flange 53^a having holes 53^b receiving punches 49, and said punches are 55 provided with pins or projections 57 adapted to rest upon flange 53^a, whereby the latter may lift said punches from die 51. The projections 57 are shown guided in vertical-grooves 58^a in a bar 58 shown secured on 60 guide 50, whereby punches 49 are kept from rotating, and a plate 59 secured over grooves 58^a by engaging projections 57 limit the upward movement of the punches when lifted by head 53.

65 To cause punches 49 to punch holes in the

sheets 48 as required in accordance with the perforations of master sheet 3, I provide slides 60 carried by head 53 and which are normally retracted from over the punches, and are pushed forwardly over the punches by devices connected with pneumatics that are controlled by the master sheet passing over bridge 2. The slides 60 are guided in suitable ways or grooves 61 provided in head 53 which may be formed between lugs 61^a 70 formed on the corresponding parts of head 53 (Figs. 10 and 11), and said slides are shown pivotally connected with rods 62 which are pivotally connected with levers 63 pivotally supported by cross bars 64 supported upon frame 1. Said cross bars 64 are provided with pneumatics for operating levers 63, shown enlarged in Figs. 15 and 16. The pneumatics illustrated are formed by providing the bars 64 with a suitable number of 80 chambers or pockets 65 in one face and placing over their open ends diaphragm 66 of suitable flexible material, such as leather, rubber cloth, or the like, and to each diaphragm in line with the corresponding chamber 65 is connected the corresponding lever 63, as by means of a stud 67 having a threaded portion passing through the diaphragm and held by a nut 68, a washer or flange 69 on the opposite side of the diaphragm in conjunction with nut 68 serving to make air tight joints at the diaphragm. The levers 63 are pivotally connected with the corresponding studs 67 by pins 70, and springs 71 acting with said levers serve to 90 draw the diaphragms outwardly and thereby move levers 63 to cause them to push rods 62 to move the corresponding slides 60 over the associate punches 49. I have shown springs 71 as coiled around the pivots 72 of levers 63, and having one end bearing against pin 70 and the other end against bar 64. 100

The diaphragms 66 may be made by a long strip of flexible material pasted on the face of bar 64 to close all the chambers 65 air tight, although separate diaphragms for one or more pneumatic chambers 65 may be provided if preferred. In order to permit assembling of studs 67 of the pneumatics upon the diaphragm or diaphragms I have shown the rear walls of chambers 65 as provided with openings 65^a through which the corresponding nuts 68 may be manipulated, and to the outer face of bar 64 I paste suitable material, such as leather, rubber cloth, or the like 110 73 to close the openings 65^a, providing air tight pneumatic chambers. Chambers 65 are connected with corresponding orifices of bridge 2, and to this end the passage 65^b of each pneumatic chamber 65 in the bars 64 120 is connected, as by rubber tubes 74, with the bores 2^b of the corresponding orifices 2^a of the bridge. The bridge is provided with a longitudinally disposed suction-chamber 2^c 125 that communicates through ports 2^d with 130

the corresponding bores 2^b of the bridge. The chamber 2^c is connected by a suitable tube 2^e with any suitable air suction pump (not shown) for maintaining suction in chamber 2^c. Each port 2^d is adapted to be controlled as required by the tapered end 75 of a screw 75^a meshing in a threaded hole in bridge 2 (see Fig. 14) for regulating the flow of air from bores 2^b into suction chamber 2^c to permit the proper amount of air to enter the corresponding pneumatic while still permitting the proper flow of air from the pneumatic to the suction chamber 2^c. When a perforation in the master sheet passes over an orifice in bridge 2 air passes through the corresponding bore 2^b and tube 74 into the associate pneumatic chamber 65 relieving the suction therein, and the corresponding spring 71 operates lever 63 to push the corresponding slide 60 over the associate punch 49, and thereby as head 53 continuously reciprocates such punch will be caused to punch a hole in the stock sheet or sheets 48 corresponding to the perforation in the master sheet then over the corresponding orifice, and so on for the various pneumatics in accordance with the perforations of the master sheet passing over the orifices of the bridge. When the master sheet next closes said orifice in the bridge the air from the corresponding pneumatic is sucked into chamber 2^c of the bridge, and then the corresponding diaphragm 66 pulls back against spring 71, overcoming the same, and thereby lever 63 pulls the corresponding slide 60 from over its punch, all whereby when the imperforated part of the master sheet is over the orifices of the bridge the corresponding slides will be held retracted from over their punches, and whereby when the perforations of the master sheet align with orifices of the bridge the corresponding slides 60 will be pushed over their punches to cause the stock sheets 48 to be correspondingly punched in accordance with the perforations of the master sheet.

While I have above described a convenient form of pneumatics for operating slides 60, it will be understood that the same may be altered to accomplish the same results, and to this end in Figs. 17 and 18 I have shown a modification of the pneumatics as follows: The studs 67 are secured air tight to diaphragm 73 and the heads of said studs bear against diaphragm 66 and lie within chamber 65, and over each diaphragm 66 is a chamber 76 communicating by a tube 74 with the corresponding bore 2^b of the bridge. A suction chamber 64^a in bar 64, (having a suction pipe 64^b connected to the suction pump connected with chamber 2^c) is provided with ports 64^c leading to chambers 65 for permanently maintaining suction in said chambers 65. The relative positions of diaphragms 66 and 73 when the orifices in bridge 2 are closed by sheet 3 is such as normally to hold levers 63

in position to retract slides 60 from their punches and the suction thus maintained in chambers 76 through tubes 74 from chamber 2^c of the bridge, rarefies the air in chambers 76 to the same degree as maintained in chambers 65 permitting diaphragm 73 to rock levers 63 to pull the slides 60 from the punches, and when an orifice of the bridge is opened by a hole in sheet 3 air enters the corresponding chamber 76 whereby suction 75 in chamber 65 pulls diaphragm 66, which being of greater area than diaphragm 73 pushes stud 67 causing it to operate lever 63 to push its slide 60 over its punch 49.

Pulley 28 is mounted loosely upon shaft 27 and any suitable clutch may be provided to rotatively connect said pulley and shaft, which clutch may be thrown into and out of action by a lever 80 pivotally supported upon frame 1 and having a slide bar 81 to control the clutch, adapted to cause shaft 27 to stop in such positions that head 53 will be elevated to hold punches 49 above sheets 48; and a brake 82 checks the momentum of shaft 27 (Fig. 4) in manner similar to clutches in die presses.

The stock sheet or sheets 48 to be perforated are drawn between guide 50 and die 51 step by step as required, and in order to positively and uniformly draw a plurality of super-imposed sheets simultaneously so that the punches 49 may accurately and correspondingly punch such sheets simultaneously I provide the following arrangement: at 85, 86 are shafts journaled in frame 1 and carrying sprocket wheels 87, 88 respectively near opposite ends, over which wheels chains 89 pass and to said chains are attached cross bars 90 at suitable distances apart, the ends of which bars travel in guide grooves 91 in 100 horizontally disposed guides 92 secured upon frame 1 on opposite sides thereof. Near opposite ends of the bars 90 are pivotally supported grippers for the sheets 48 to hold the latter firmly to said bars. These grippers 110 are shown comprising bell-crank levers 93 pivotally supported upon lugs 94 on said cross bars and provided at their inner ends with spring pressed toothed gripping members or plungers 95 (Figs. 19 and 20) which 115 are shown provided with stems 96 supported in bearings in levers 93 and engaged by corresponding springs 97 interposed between the grippers and guides 93^a for normally pressing the grippers toward sheets 48, washers 98 limiting the thrust of grippers 95 by springs 97. The outer arms 93^c are adapted to engage the inner faces 92^a of guide 92 to cause the gripper levers 93 to rock and press the grippers 95 firmly upon sheets 48 (in the position shown in Fig. 20), and said gripper levers 93 are normally pressed outwardly away from sheets 48 by springs 100 to release the grippers from sheets 48. To cause the grippers to engage sheets 48 as the grippers 130

travel in the direction of the arrow in Fig. 5, the forward ends ^{92b} of guides 92 are inclined upwardly and in the direction of travel of the sheets, so that when the gripper levers 93, which are normally swung outwardly by springs 100, are carried by chains 89 to the front lower corners of guides 92 the arms ^{93c} will engage the inclines ^{92b} and by riding up on the same the levers 93 will be turned over sheets 48 to press the grippers 95 upon said sheets to grip the sheets to bars 90, and arms 93 will slide along faces ^{92a} holding the grippers in engagement with the sheets and thereby pulling the sheets along with the chains until arms ^{93c} pass from the ends ^{92c} of guides 92, whereupon springs 100 will swing the gripper levers 93 outwardly and lift the grippers 95 away from the sheets, and out of vertical alinement therewith, to permit the grippers to pass the edges of the sheets as the grippers are carried around by the chains 89. Thus, several grippers may simultaneously grip sheets 48 upon cross bars 90 and assure that said sheets are pulled equally and simultaneously beneath the punches. The sheets 48, between the punches and the grippers preferably slide upon the supporting plate 101.

The sheets 48 are to be pulled simultaneously and coincidently with the travel sheet 3, and to an extent proportioned to the length of the respective perforations and spacing desired in sheets 48. To this end I provide shaft 86 with a detachable gear 102 that meshes with a gear 103 pivotally carried by an arm 104 hung upon or concentric with shaft 38, and gear 103 meshes with a gear ^{103a} secured on shaft 38, or secured to ratchet 39, and by means of arm ^{24a}, link 36, arm 37, dog 40, and ratchet 39, the shaft 86 will be rotated step by step simultaneously with the step by step feeding of drum 13 by ratchet 22. Gears 102 of different diameters may be used as desired in accordance with the step by step feeding movement desired for sheets 48, so that said sheets may be fed a greater or less distance each step according to the length of perforations and spacing desired in sheets 48, and arm 104 may be held in set position, in accordance with the gear 102 being used, by means of a screw 105 meshing in a threaded aperture in frame 1 and passing through a curved slot ^{104a} in arm 104 (Fig. 1). For greater range of adjustment of arm 104 the screw 105 may be set in a hole 106 when the diameter of gear 102 has been correspondingly increased.

In order to guide sheets 48 accurately through space 52 under the punches, I provide guide fingers 107 that project upwardly from blocks 108 (Figs. 2, 3 and 5) in front of space 52, which blocks travel in ways 109 of bed 110 (Fig. 5) and at 111 is a shaft journaled to rotate in a support 112 (Fig. 2) but having no longitudinal movement, which

shaft near its ends has right and left threads ^{111a} engaging corresponding threads in blocks 108, a handle 113 on said shaft permitting it to be rotated. By rotating shaft 111 to the right or left the guides 107 will be caused to approach or recede to centrally guide sheets 48 as they travel under punches 49.

I have shown means for winding the perforated sheets 48 upon music spools 115 supported upon a frame ^{1a} at the end of frame 1 or as an extension thereof. One end of the shaft ^{115a} of each spool 115 is supported to rotate in a bearing 116 shown carried in a socket piece 117 supported on side bar ^{1b} of frame ^{1a} and containing a spring 118 to press said bearing outwardly, a screw 119 passing through a hole in said socket piece and screwed into bearing 116 limiting the thrust of the latter by said spring (see Figs. 23 to 27). The shaft portion ^{115b} of each spool 115 enters a socket ^{120a} in a shaft 120 journaled in a bearing in a side bar ^{1b}, and shaft ^{115b} is shown provided with projections ^{115c} that enter slots ^{120b} in the ends of shafts 120, whereby spool 115 is rotated. Bearings 116 may be pushed back to permit the insertion of spools 115 into and removal from their bearings. Shafts 120 are provided with pulleys or rolls 121 upon which a belt 122 travels for rotating the spools 115, said belt passing over pulleys 123 and 124, pulley 123 being loose on a shaft 125 journaled on frame ^{1a}, pulley 124 being loose upon a shaft 126 supported on frame ^{1a}. Shaft 125 has fast and loose pulleys 127, 128 and also carries a fast pulley 129 from which a crossed belt 130 passes over pulley 124 for rotating the latter; shaft 125 also carries a fast pulley 131, and shaft 126 carries a pulley 132, over which pulleys a belt 133 passes upon which belt the sheets 48 rest.

At 135 are friction rollers bearing upon belt 122 and serving to press the latter upon the corresponding pulleys 121, and the pulleys 135 are pivotally carried upon arms 136 which may be arranged in pairs on opposite sides of each roller 135 (see Fig. 23), in the outer ends of which arms the shafts 137 of rollers 135 are journaled. Said arms 136 are pivotally supported upon bars ^{1b} and their rollers 135 are independently held pressed upon belt 122 by weights 138 connected with the outer ends of arms 136 by suitable connections 139. With the arrangements above described, the sheets 48 are passed over belt 133 and respectively connected with corresponding music spool 115, and driving belt 140 on pulley 128 may continuously rotate said belts, and as belt 122 is rotated in the direction of the arrow ^x in Fig. 22 the music spools will be caused to rotate to wind sheets 48 thereon respectively, and belt 122 will slip upon pulleys 121 as required to relieve the strain on sheets 48, belt 130

133 assisting in supporting and carrying said sheet along.

The reels 48^a of the paper rolls for the sheets 48 to be perforated may be supported in a suitable frame A located adjacent the punches 49, from which said sheets may pass one upon the other through space 52 (see Figs. 27 to 32). Said reels at one end are supported upon pivots 48^b adjustably 10 carried by blocks 48^c secured upon frame A, and the opposite ends of said reels are detachably connected with short shafts 48^d journaled in blocks 48^e secured upon the opposite side of said frame. The shafts 48^d 15 are shown provided with recesses 48^f at one end receiving the ends of the shafts of reels 48^a, shafts 48^d also having slots 48^g receiving pins 48^h on the shafts of the reels, all whereby said reels may be detachably connected with pivots 48^b and shafts 48^d. Slack in the sheets 48 between their reels 48^a 20 and punches 49 may be pulled out by hand to reduce strain on sheets 48 as they are drawn from the reels, and as a convenient 25 means for producing such slack in said sheets I have shown shafts 48^d as provided with sprocket wheels *a* receiving endless chain *b* for rotating said reels. On one of the shafts 48^d is journaled a sleeve *c* provided with a 30 crank or handle *d* carrying a sprocket *e* receiving a chain *f* from a sprocket *g* secured on a shaft 48^d for operating chain *b*.

I have shown the reels and their shafts 48^a as arranged in series of three tiers, and the 35 chain passes over some sprockets and under other sprockets, whereby the chain is caused to properly engage said sprockets for producing the desired slack simultaneously in the various sheets 48 at will. The sheets 40 will pass properly from their reels according to the direction of rotation thereof. I have also shown means whereby duplicate master sheets 18 may be produced in accordance with master sheet 3, and for this purpose 45 I provide the following arrangement: At one end of frame 1 adjacent punches 49 is journaled a shaft 141 in suitable brackets 142 upon which shaft may be mounted a roll or drum 143 provided with pins 144 (Fig. 17) arranged similarly to roll or drum 13 and its pins. Shaft 141 also carries a ratchet wheel 145 engaged by a spring pressed pawl 146 pivotally carried by an arm 147 journaled on shaft 141 and pivotally 50 connected by a link 148 with arm 24^a (Fig. 1), the arrangements being such that drum 143 will be rotated step by step simultaneously and coincidently with the rotation of drum 13. To cause the duplicate master 55 sheet 18 (Fig. 28^a) to be drawn along under punches 49 by drum 143 I provide means for producing the perforations 18^a near the edges of sheet 18 to engage pins 144 of drum 143. To this end the punches 49^a (see Fig. 65 3) at the ends of the series of punches 49 are

controlled separately from the punches 49, as by corresponding pneumatics, and said punches 49^a are to punch the holes 18^a in sheet 18 at definite distances apart and preferably corresponding to the holes 3^a at the 70 sides of master sheet 3, irrespective of the perforations 18^b produced in sheet 18 for the musical composition. To this end I connect the passage 65^b of the pneumatics of the end punches 49^a with a tube 150 (Fig. 3), a 75 tube 151 extending from tube 150 to one end of suction chamber 2^c of bridge 2, (Figs. 1 and 7) and the tube 152 extending from the opposite end of said chamber and being connected with a coupling 153 from which a 80 tube 154 leads to tube 150. Coupling 153 connects by a tube 155 with a passage 156 (Figs. 4 and 13) in a block 157 secured on frame 1, the other end or port of which passage is controlled by a valve 158 carried by a 85 spring or arm 159 operated by a dog 160. Dog 160 is pivotally supported, as at 161, upon frame 1 and is provided with a spring 162 to cause the end 160^a of said dog to normally tend to lift spring 159 and valve 158, 90 and the end 160^b of said dog engages a toothed wheel 163 on shaft 141. When dog 160 rides upon the surface of wheel 163, arm 160^a will release spring 159 and valve 158 will close passage 156, and when the end 160^b of dog 160 enters a notch in wheel 163 its end 160^a will raise spring 159 and valve 158 and open passage 156. The effect of this is that when arm 160^b enters a notch in wheel 163 air 100 enters passage 156 and flows through tubes 154 and 150 to the corresponding pneumatics 65 of the end punches 49^a, whose springs will then push the end slides 60^a over punches 49^a, so that upon the next descent of head 53 holes 18^a will be punched near the edges 105 of sheet 18, and when arm 160^b at the next stroke of arm 147 rides up on the surface of wheel 163, valve 158 will close passage 156 and the suction through tubes 151 and 152 communicating with the corresponding pneumatics 65, will cause their diaphragms 66 to operate their levers 63 to pull back slides 60^a 110 from punches 49^a, which will be held retracted until arm 160^b again enters the next notch in wheel 163, and so on each time that 115 said arm enters a notch in wheel 163, holes 18^a at opposite ends of sheet 18 will be punched, thereby producing series of such holes in said sheet at definite distances apart corresponding to the distances between pins 120 13^a of drum 13 and pins 144 of drum 143.

The duplicate master sheets 18 produced as above set forth may be used the same as master sheets 3, whereby the duplicating of master sheets may be simplified and their cost reduced. The master sheets 18 are fed through the machine in the direction reverse to the feeding of sheets 48 as shown by the arrow *y* in Fig. 6. When the master sheet 18 is to be produced the guides 92 may be 125

removed to permit the gripper levers 93 that extend upwardly from chains 89 to swing outwardly away from sheet 18, and the latter may slide over across bars 90 and plate 5 101, and the gears of chains 89 may be stopped, as by disconnecting link 36, to prevent movement of the chains. I have shown tube 150 connected at opposite ends by tubes 151, 154 and 152 with suction 10 chamber 2^e to assure sufficient suction in the corresponding pneumatics 65 for quick simultaneous action of the end slides 60^a.

In Fig. 1 I have shown suction tube 2^d connected with a three-way cock 165 from 15 which a tube 166 may lead to a suction pump, (not shown) and a tube 167 may lead to an air force pump, whereby when valve 165 is turned to one position suction through the pneumatic devices may be produced, 20 and when turned to another position the suction pump will be cut off and the force pump may supply air under pressure through tubes 167 and 2^e to blow dust and accumulations out of the ports 2^e and orifices 2^a.

25 The operation of my improvements as above set forth may be described as follows: The master-sheet roll 4 being mounted in its bearings, said sheet is placed under guide 12, over bridge 2, under bar 29, over drum 13 30 and its holes 3^a fitted upon pins 13^a, thence under roll 35, and its end attached to take up reel 33, the bar 29 then being adjusted to cause perforations 3^b to properly track over the orifices of the bridge; the head 53 is elevated and sheets 48 are passed through space 52 from their reels and are carried forward and fitted on cross bars 90 and held by grippers 95, chains 89 then being suitably operated by means of handle 85^a on shaft 85

40 (Fig. 1). Pulley 28 is then connected by the clutch with shaft 27, head 53 reciprocates, and drum 13 and grippers 95 are advanced step by step, the latter pulling sheets 48 simultaneously under the punches, and drum 45 13 pulls sheet 3 across the bridge. As the perforations 3^b of said sheet pass over the orifices of bridge 2 the corresponding pneumatics 65 will push the corresponding slides 60 over the associate punches 49, but the

50 relation of the parts is such that said slides will be pushed outwardly only at such times as the punches are elevated from sheets 48, for the step by step movements of drum 13 and grippers 95 only take place when punches 55 49 are above sheets 48, and during the periods of rest of said drum and grippers the operating slides 60 are held over the punches and head 53 and the punches then descend, but such punches 49 as are not at such time 60 opposed by projecting slides 60 normally rest on the uppermost sheet 48 during the descent of head 53 without perforating the sheets. It will thus be understood that by reason of the step by step feeding of master 65 sheet 3 and stock sheets 48 sufficient time of

rest is provided for head 53 to lift the punches from sheets 48, whereupon during the step forward of said sheets the slides 60 are appropriately shifted as required to produce the desired perforations in sheets 48 70 during the next down stroke of head 53 while the sheets 48 are at rest, and so on. When duplicate master sheet 18 is to be perforated a similar simultaneous feeding of sheets 3 and 18 takes place, while during the 75 periods of rest of said sheets the punches are operated, and at the proper times arm 160^b of dog 160 enters the notches in wheel 163 to cause the corresponding pneumatics 65 to push the slides 60^a over punches 49^a, 80 to cause holes 18^a to be punched in master sheet 18 at the appropriate distances apart, irrespective of the perforations 18^b at such time being made in sheet 18.

My invention is not limited to the particular details of construction and relative arrangements of parts above described, as the same may be varied without departing from the spirit thereof.

Having now described my invention what I claim is:

1. The combination of a bridge provided with orifices and having a suction chamber communicating with said orifices, pneumatics respectively in free and uncontrolled communication with said orifices, levers operated by said pneumatics, a reciprocative head, a plurality of punches independent thereof, slides carried by the head to co-act with the punches and connected with said levers, and means to draw a master sheet across said bridge.

2. The combination of a bridge provided with orifices and having a suction chamber communicating with said orifices, pneumatics respectively in free and uncontrolled communication with said orifices, levers operated by said pneumatics, a reciprocative head, a plurality of punches independent thereof, slides carried by the head to co-act with the punches, means to move a master sheet 105 across said bridge step by step, and means to draw sheets across the punches step by step simultaneously with the movement of the master sheet.

3. The combination of a bridge provided with orifices, and having a suction chamber communicating with said orifices, means to draw a master sheet across the bridge, a plurality of cross bars each provided with chambers, tubes connecting said chambers 120 respectively with the orifices of the bridge, diaphragms closing said chambers, levers connected with said diaphragms, a reciprocative head, a plurality of punches independent thereof, and slides carried by the 125 head to co-act with the punches and connected with said levers.

4. The combination of a bridge provided with orifices and having a suction chamber communicating with said orifices, a plurality 130

of cross bars each provided with chambers, tubes connecting said chambers respectively with the orifices of the bridge, diaphragms closing said chambers, levers connected with 5 said diaphragms, a reciprocative head, a plurality of punches independent thereof, slides carried by the head to co-act with the punches and connected with said levers, means to draw a master sheet across the bridge step by step, 10 and means to draw sheets across the punches step by step in accordance with the step by step movement of the master sheet.

5. The combination of a bridge provided with orifices and having bores communicating therewith, a suction chamber provided with ports communicating with said bores, pneumatics provided with diaphragms and having tubes connecting them with said bores respectively, independent of the suction 15 chamber, levers connected with said diaphragms, a reciprocative head, a plurality of punches independent thereof, slides carried by said head to co-act with the punches and connected with said levers, 20 and means to draw a master sheet across the bridge.

6. The combination of a bridge provided with orifices and having bores communicating therewith, a suction chamber provided with ports communicating with said bores, pins to regulate the passage of said ports, means for adjustably supporting said pins, pneumatics having tubes connecting them with said bores respectively, a reciprocative 30 head, a plurality of punches independent thereof, movable members carried by said head to co-act with the punches, means connecting said members with said pneumatics respectively, and means to draw a 35 master sheet across said bridge.

7. The combination of a bridge movably supported at one end and having an adjustable support at the opposite end, a bearing for said support, a spring acting with said 45 bridge to move the same lengthwise, means for drawing said bridge against the tension of said spring, means to draw a music sheet across the bridge, a reciprocative head, a plurality of punches independent of said 50 head, and means interposed between said punches and said bridge and flexibly connected with said bridge for controlling said punches according to the perforations of said sheet.

8. The combination of a bridge, a drum comprising a plurality of members adjustable with respect to each other, each member having an annular row of pins, a shaft to which one member is secured, a nut connected with said shaft to operate the opposite member, a spring co-acting with said member and against said nut, means to support and rotate said shaft, a reciprocative head, a plurality of punches and means interposed between said punches and said

bridge for controlling the punches according to a music sheet passing over said bridge and drum.

9. The combination of a bridge, means for supporting a master music sheet roll, a 70 pulley, devices connecting the support of said roll with said pulley for rotating the roll thereby, means for movably supporting said pulley, a shaft provided with a pulley to operate the first named pulley, a take up 75 roll for the sheet, a reciprocative head, a plurality of punches, means interposed between said punches and said bridge for operating the punches according to the perforations in said sheet, a drum to draw the 80 sheet across the bridge, and means for operating said drum step by step.

10. A perforating apparatus, comprising a bridge, a reciprocative head, a plurality of punches, devices to co-act with said punches, 85 means interposed between said devices and said bridge adapted to be controlled by a master sheet passing over the bridge for operating said punch controlling devices in accordance with the perforations in the master sheet, means to move the master sheet across the bridge step by step, a plurality of chains, means to operate said chains step by step, cross bars carried by said chains, grippers pivotally supported upon said bars, guides 90 at the sides of the grippers provided with longitudinal faces to hold the grippers in contact with sheets, said guides having means at their forward ends to cause the grippers to swing over upon the sheets, and 95 means to swing the grippers over outwardly away from the sheets when released from the guides.

11. A perforating apparatus, comprising a bridge, a reciprocative head, a plurality of 105 punches, devices to co-act with said punches, means interposed between said devices and said bridge adapted to be controlled by a master sheet passing over the bridge for operating said punch controlling devices in accordance with the perforations in the master sheet, means to move the master sheet across the bridge step by step, a plurality of 110 chains, means to operate said chains step by step, cross bars carried by the chains, guides 115 at the ends of the cross bars, grippers pivotally carried by the cross bars and comprising levers provided with spring-pressed members at one end to engage sheets on the bars, the opposite ends of said levers being arranged to engage longitudinal faces of the guides to hold the grippers upon the sheets, means at the ends of the guides to cause the grippers to swing over upon sheets and arranged to release said grippers when they 120 pass from said guides, and springs to normally hold said grippers away from the sheets.

12. A perforating apparatus, comprising a bridge, a reciprocative head, a plurality of punches, devices to co-act with said punches, 130

- means interposed between said devices and said bridge adapted to be controlled by a master sheet passing over the bridge for operating said punch controlling devices in accordance with the perforations in the master sheet, means to move the master sheet across the bridge step by step, a plurality of chains, means for operating said chains step by step, cross bars carried by said chains, guides at the ends of said cross bars provided with horizontally disposed grooves receiving the ends of the cross bars, levers pivotally supported upon said cross bars, springs connected with said levers to normally swing them outwardly, gripper members movably carried by the inner arms of said levers and provided with springs to normally push the grippers toward sheets on the cross bars, said guides having longitudinal faces against which the outer ends of the levers bear, the forward ends of said guides being inclined upwardly to engage the outer ends of said levers to engage the grippers upon the sheets as the chain travels.
13. The combination of a plurality of punches, means for operating said punches in accordance with the perforations in a master sheet, and means for drawing a plurality of sheets across said punches, with a plurality of rolls to wind up the sheets perforated by the punches, means for supporting said rolls, pulleys connected with said rolls, a belt passing over said pulleys, means to operate said belt, and means to press said belt independently upon each of said pulleys.
14. The combination of a plurality of punches, means for operating said punches in accordance with the perforations in a master sheet, means to draw a plurality of sheets across said punches, with a plurality of rolls to wind up the sheets perforated by the punches, means for supporting said rolls, pulleys connected with said rolls, a belt passing over said pulleys, means to operate said belt, and rollers bearing upon said belt opposite the corresponding pulleys to cause said belt to beat independently upon said pulleys.
15. The combination of a plurality of punches, means for operating said punches in accordance with the perforations in a master sheet, and means to draw a plurality of sheets across said punches, with a plurality of rolls to wind up the sheets perforated by the punches, means for supporting said rolls, pulleys connected with said rolls, a belt passing over said pulleys, means to operate said belt, rollers bearing on said belt opposite the corresponding pulleys, arms carrying said rollers, and weights connected with said arms.
16. The combination of a plurality of punches, means for operating said punches in accordance with the perforations in a master sheet, and means to draw a plurality of sheets across said punches, with a plurality of rolls to wind up the sheets perforated by the punches, means for rotating said rolls coincidently and for relieving the strain on the sheets wound on the rolls as required, and an endless belt below said rolls to receive said sheets.
17. The combination of a plurality of punches, means for operating said punches in accordance with the perforations in a master sheet, and means to draw a plurality of sheets across said punches, with a plurality of rolls to wind up the sheets perforated by the punches, means for rotating said rolls coincidently and for relieving the strain on the sheets wound on the rolls as required, reels for said sheets, means for supporting said reels, and means for turning said reels at will to provide slack in said sheets.
18. The combination of a plurality of punches, means for operating said punches in accordance with the perforations in a master sheet, and means to draw a plurality of sheets across said punches, with a plurality of rolls to wind up the sheets perforated by the punches, means for rotating said rolls coincidently and for relieving the strain on the sheets wound on the rolls as required, rolls for said sheets, a frame, shafts carried by said frame for supporting said rolls, sprockets connected with said shafts, and a chain engaging said sprockets and provided with means for operating it at will to provide slack in said sheet.
19. The combination of a bridge, means to draw a master sheet across the bridge, a reciprocative head, a series of punches, movable members to co-act with the punches, pneumatics connected respectively with the orifices of the bridge, and provided with means respectively connected with corresponding movable members to cause said members to coact with the punches in accordance with the perforations in the master sheet, the pneumatics for the members at the ends of the series of punches being connected with an exhaust chamber, and a valve to admit air to said pneumatics, a dog to control said valve, a drum provided with pins near opposite ends to draw a sheet across the punches, a toothed wheel connected with said drum and adapted to co-act with said dog, and means to rotate said drum step by step, whereby when said dog enters a notch in the wheel the valve will open to cause the corresponding pneumatics to operate said end members to cause the end punches to punch holes near the edges of the sheet drawn by said drum.
20. The combination of a bridge, means to draw a master sheet across the bridge, a reciprocative head, a series of punches, slides connected with the head to co-act with the punches, pneumatics connected respectively with the orifices of the bridge and provided with movable members respectively con-

nected with corresponding slides to cause said slides to co-act with the punches in accordance with the perforations in the master sheet, the pneumatics connected with the 5 slides at the ends of the series of punches being respectively connected by pipes with an exhaust chamber, one of said pipes being provided with a valve, a dog to actuate said valve; a drum provided with pins to draw a sheet across the punches, a toothed wheel connected with said drum to co-act with said dog, and means for operating said drum step by step.

21. The combination of a bridge provided 15 with orifices and a suction chamber communicating therewith, means to draw a master sheet step by step across the bridge, a reciprocative head, a series of punches, slides to act with the punches, pneumatics connected 20 with the orifices of the bridge and provided with movable members respectively connected to corresponding slides, pipes con-

necting the pneumatics of the slides at the ends of the series of punches with said suction chamber, a valve to control the flow 25 through said pipes, a dog to control said valve, a drum provided with pins to draw a sheet across said punches, a toothed wheel connected with said drum to co-act with said dog, a ratchet connected with said drum, a 30 pawl to operate said ratchet, a rock arm carrying said pawl, and means connecting said arm with the means that operate the master sheet to draw the sheet to be perforated across said punches simultaneously with and 35 according to the step by step movement of the master sheet.

Signed at New York city, in the county of New York, and State of New York, this 28th day of June A. D. 1907.

HARRY M. SALYER.
